UNITED STATES PATENT OFFICE.

ALBERT ZAVELBERG, OF HOHENLOHEHÜTTE, GERMANY.

ROASTING-FURNACE.

1,107,006.

Specification of Letters Patent. Patented Aug. 11, 1914.

Application filed May 14, 1914. Serial No. 838,529.

To all whom it may concern:

Be it known that I, ALBERT ZAVELBERG, engineer, subject of the German Emperor, residing at Hohenlohehütte, Silesia, Germany, have invented new and useful Improvements in Roasting-Furnaces, of which the following is a specification.

In roasting furnaces generally rotary rakes are employed for raking the charge, for turning the latter over, moving it into lower layers and finally conveying it to the dischargers. These known rakes, however, have the following disadvantages: The mechanical resistance, which the raking arms meet in raking and advancing the charge, results in, owing to the metal being softened by the high temperature, considerable deformations. These deformations will, of course, very greatly reduce the efficiency of the raking gear, and when such deformations are so great that they prevent the passage of the raking arms through the comparatively low chambers of the furnace they may even stop the operation of the furnace altogether. An exchange of such deformed raking arms in furnaces of the known types, however, is rather difficult, particularly because they must be secured to the inner, central shaft. For instance, the raking arms are pushed into the furnace and engaged with devices provided on the said central shaft. Such exchanging of defective raking arms will, therefore, always necessitate a lengthy interruption of the work and thus represent a loss in time and money, in particular, because the furnace cools down during such interval and must then be started afresh. With the object of avoiding these disadvantages the rakes are, according to the present invention, fitted to a framework, traveling on the outside around the furnace and project from this framework through circular slots in the furnace wall into the furnace. The raking arms are thus constantly within the furnace. The framework does not only serve to support the raking arms, but the motion of the framework is at the same time the source of power for operating the raking arm.

As the raking operation produced according to the present invention is a continuous one, the slots, through which the raking arms project into the furnace have the shape of circular slots. The framework carrying the raking arms, furthermore serves as a

support for the overhanging roofs of the roasting chambers.

In the accompanying drawing a constructional form of the present invention is exemplified.

Figure 1 is a vertical section through the furnace. Fig. 2 is a horizontal section on the line A—A in Fig. 1. Fig. 3 illustrates, on an enlarged scale, the method of forming the outside joint of the raking arms. Fig. 4 is a top view of Fig. 3. Fig. 5 is a vertical section through another constructional form of the furnace. Fig. 6 illustrates the flues for the fire gases.

As an example, it shall be assumed that the furnace has three roasting levels a , a^1 and a^2 . The charge is admitted through the hopper b , and conveyed by the worm c to top floor a of the furnace. Thence the charge is gradually raked to the lower levels, and finally it is, after completion of the roasting, discharged at d .

The raking arms e are fitted to a framework f , adapted to travel around the furnace, and project from this framework through circular slots g into the several floors of the furnace. By the traveling motion of the framework the raking arms e are simultaneously drawn through the several levels of the furnace whereby the charge is raked and conveyed.

The roasting gases enter into the flue k and are then conducted twice around the furnace, reversing the direction of their flow. They then rise through the flue k^1 , pass down again through flue k^3 and escape at k^5 .

The air is supplied through the flues k^4 , is heated by passing along the heating flues, then, thus heated, it flows through the roasting chambers and escapes through the flue k^5 .

Above the roasting levels a chamber is provided in which the fine dust and ashes shall collect. This chamber is provided with cleaning doors in the wall of the furnace. The framework f is moved by means of a gearing, a pinion n on the framework rolling on a rack o .

The manner in which the raking arms e are jointed toward the outside is shown in Figs. 3 and 4. This object is obtained by jointing plates of an annular shape with bent over edges, s and s^1 engaging in likewise annular gutters q extending around the

whole periphery of the furnace and filled with sand and the like. The said plates are secured in a suitable manner to the raking arms.

5. In consequence of the arrangement of the raking arms according to the present invention the roofs of the roasting chambers have to overhang and therefore require some support at their outer ends. This is obtained in 10 the following manner. The ends of these roofs *t* are supported on the traveling framework *f*. To the periphery of these roofs angles are secured. The lower flange *w* of which rides on rollers *r* or ball bearings, 15 two of which are provided on each frame section for each level.

In Fig. 5 a somewhat different constructional form of the furnace according to the present invention is exemplified. Here a 20 space within the furnace has been left clear to receive the traveling framework. This constructional form has the advantage that the framework has to bear a much smaller weight, as, owing to the diameter of the furnace decreasing toward the center, the roofs of the roasting chambers overhang for a 25 shorter distance.

I claim:

1. In a roasting furnace the combination 30 with a track encircling said furnace, of a plurality of horizontal slots formed in the side of said furnace, a truck and its complementary tower mounted on said track,

rakes provided with slot closures mounted on said tower and adapted to enter said slots, 35 said rakes operated through medium of said traveling truck and tower, and means coacting with said frame to support said roof, substantially as described.

2. In a roasting furnace the combination 40 of a track adjacent one wall thereof, a truck and its complementary tower, mounted on said track, roof projections for said furnace, means carried by said tower adapted to support said roof, longitudinal slots disposed 45 within said wall adjacent said roof and rakes secured to said tower provided with movable closures for said slots, substantially as described.

3. In combination with a roasting furnace, 50 longitudinal slots therein, rakes adapted to enter said furnace through said slots, independent traveling supporting members serving to carry said rakes, roof projections for said furnace, said members 55 adapted to carry roof supports adapted to engage said projections, slot closures carried by said rakes, substantially as described.

In testimony whereof I have signed my name to this specification in the presence of 60 two subscribing witnesses.

ALBERT ZAVELBERG.
